Primary Examiner — Kevin Rudzinski(74) *Attorney, Agent, or Firm* — Jianq Chyun IP Office(57) **CLAIM**

The ornamental design for a portion of a display screen with graphical user interface, as shown and described.

DESCRIPTION

The FIGURE is a front view of a portion of a display screen with graphical user interface showing our new design. The broken line showing of a portion of the display screen is for the purpose of illustrating environmental structure and forms no part of the claimed design. The broken lines showing the portions of the graphical user interface form no part thereof.
